[57] CLAIM

The ornamental design for a minnow bucket, as shown and described.

DESCRIPTION

FIG. 1 is a perspective view of the minnow bucket embodying my new design, showing an outer bucket having an inner bucket inserted therein;

FIG. 2 is a front, elevational view of the minnow bucket shown in FIG. 1;

FIG. 3 is a rear, elevational view of the minnow bucket shown in FIG. 1;

FIG. 4 is a top, plan view of the minnow bucket shown in FIG. 1;

FIG. 5 is a bottom, plan view of the minnow bucket shown in FIG. 1;

FIG. 6 is a perspective view of the outer bucket shown in FIGS. 1 through 5;

FIG. 7 is a front, elevational view of the outer bucket shown in FIG. 6;

FIG. 8 is a rear, elevational view of the outer bucket shown in FIG. 6;

FIG. 9 is a top, plan view of the outer bucket shown in FIG. 6;

FIG. 10 is a bottom, plan view of the outer bucket shown in FIG. 6;

FIG. 11 is a perspective view of the inner bucket shown in FIGS. 1 through 5;

FIG. 12 is a front, elevational view of the inner bucket shown in FIG. 11;

FIG. 13 is a rear, elevational view of the inner bucket shown in FIG. 11;

FIG. 14 is a top, plan view of the inner bucket shown in FIG. 11; and

FIG. 15 is a bottom, plan view of the inner bucket shown in FIG. 11.

*Fig. 12.**Fig. 13.**Fig. 14.**Fig. 15.*
